UNITED STATES PATENT OFFICE.

WILLIAM J. MOXLEY, OF CHICAGO, ILLINOIS.

DESIGN FOR A BUTTER OR OLEOMARGARIN PRINT OR BRICK.

SPECIFICATION forming part of Design No. 32,577, dated April 24, 1900.

Application filed March 28, 1900. Serial No. 10,555. Term of patent 14 years.

To all whom it may concern:

Be it known that I, WILLIAM J. MOXLEY, a citizen of the United States, residing at Chicago, Illinois, have invented and produced 5 a new and useful Design for Butter or Oleomargarin Bricks or Prints, of which the following is a specification.

In the drawings, Figure 1 represents a plan view of a butter-print, and Fig. 2 represents 10 a sectional elevation taken in line 2 of Fig. 1.

As shown in the drawings, the leading or 15 important feature of my design consists in a butter or oleomargarin brick or print having on its upper or top surface a raised interior oval portion A, bordered at its sides and ends

by raised beads B, rounded at the top, as shown. These beads are of a length shorter than the length and width of the oval portion adjacent to which they are arranged, so as to leave corners in which are arranged raised ornamental designs C, representing in effect the design of a fleur-de-lis.

What I regard as new, and desire to secure by Letters Patent, is—

The design for a butter or oleomargarin 25 print or brick herein shown and described.

WILLIAM J. MOXLEY.
